UNITED STATES PATENT OFFICE.

ALEXANDER L. SCHRAM, OF HILLSBORO, ILLINOIS, ASSIGNOR TO SCHRAM GLASS MANUFACTURING COMPANY, OF ST. LOUIS, MISSOURI, A CORPORATION OF MISSOURI.

CARTON-SEALING MACHINE.

1,175,181.

Specification of Letters Patent. Patented Mar. 14, 1916.

Application filed October 6, 1914. Serial No. 865,297.

To all whom it may concern:

Be it known that I, ALEXANDER L. SCHRAM, a citizen of the United States, and resident of Hillsboro, Montgomery county, Illinois, have invented certain new and useful Improvements in Carton-Sealing Machines, of which the following is a specification containing a full, clear, and exact description, reference being had to the accompanying drawings, forming a part hereof.

My invention relates to improvements in carton sealing machines, in which a laterally swinging pressure device operates in conjunction with interchangeable bed plates; and the objects of my improvements are, first, to provide interchangeable bed plates, whereby the machine may be adapted to operate on cartons of different dimensions; and, second, to provide a pressure device which may be swung from a position covering the bed plates in order that a partially formed carton may be slipped over the bed plate and whose swinging support causes the pressure device to bear on the carton with equal pressure throughout. I attain these and other objects by the mechanism hereinafter described in detail, pointed out in my claims and illustrated by the accompanying drawings, in which:

Figure 1 shows in front elevation a machine embodying my invention, the paste pot being removed and a portion of the spacing sleeves at the top of the machine being shown in section; Fig. 2 is a side elevation of the machine as shown in Fig. 1; Fig. 3 is a perspective on a reduced scale of a carton in the condition required for the operation of the machine; and Fig. 4 is a detail sectional elevation showing the pivotal connection between the presser block and one of its suspending arms.

Referring by numerals to the accompanying drawings: 4 designates the base of the machine, arising from which is the integral standard 5 which is preferably formed hollow throughout its height. At diametrically opposite points the standard is provided with integral bearings designated by numerals 6 and paralleling at least one of said bearings is an arm 7 having its outer end perforated to receive a stem such as 8 for the support of a paste pot 9. In order to provide for altitudinal adjustment of the pot for the convenience of tall and short

operators, the stem 8 may be adjusted relative to the arm 7 by means of the set screw 10, and the pot may be adjusted relative to the stem by the set screw 11.

The numeral 12 designates the bed plate 60 or work support, which is provided with a dowel 13 arranged to fit within the open top of the standard 5. In practice I contemplate the employment of a number of different sized bed plates, as the sizes of 65 cartons operated upon dictate.

The numeral 14 designates the pressure device or presser block having on its uppermost face the bearings 15.

Carried by a flange at the top of the 70 standard is a plurality of set screws 12^a, and, formed on the bottom face of the presser block, in like arrangement with the set screws, is a number of seats to receive the ends of the set screws (as shown by 75 dotted lines in Fig. 2). By this means I can raise or lower the bed plate to compensate for different thicknesses of material and also provide a means to prevent the bed plate from rotating about the dowel 13. 80

Pivots connected with each bearing 15 is a suspending bar 16, whose upper ends are pivotally connected with a rod 17 supported by the sustaining bars 18, the sustaining bars in turn being pivotally secured to the 85 bearings 6 carried by the standard by means of the pivot pins 19. The sustaining bars 18 are each provided at their lowermost ends with angular extensions 20, which as clearly shown in Fig. 2, co-operate with the 90 stops 22, formed at opposite margins of the base 4 to limit the movement of the sustaining bars 18 when the presser block is moved from a position over the bed plate.

Each of the bearings 15 of the presser 95 block carries adjacent its rearmost end an upwardly projecting stop 23, which is arranged to engage the suspending arms at times to hold the presser block locked over "dead center" during the time the adhesive 100 is being dried, but which bearings and stop permit limited free pivotal movements between the presser block and its suspending arms forwardly of the "dead center."

For convenience in operating the presser 105 block I provide a handle 24.

At the rear margins of the presser block and projecting downwardly therefrom is a flange 25 arranged to act as a stop to limit the forward movement of the presser block. 110

By preference this flange 25 extends the entire width of the presser block and is formed at right angles to the bottom face thereof in order to engage a carton and true it over the bed plate.

In the practical operation of the machine the presser block is moved in a position from over the bed plate as shown by the dotted lines X in Fig. 2, and a carton such as shown in Fig. 3 is slipped over the bed plate and standard. The flaps A and B of the carton are then folded toward each other and rested on the top of the bed plate. The operator then applies an adhesive obtained from the pot 9 to the uppermost surfaces of the flaps A and B. The flaps C and D are then bent to partially overlie the flaps A and B and the operator then grasps the handle 24 and draws the presser block to the position shown by dotted lines Y in Fig. 2, where the presser block first engages the partially folded flaps C and D and gradually moves them toward the gummed flaps A and B. As the presser block is moved to its forward limit of movement shown by the dotted lines Z (Fig. 2) over the flaps of the carton and the bed plate, it gradually but not fully approaches parallelism therewith. Due to the construction of the bearings 15, as shown in detail by Fig. 4, it will be possible to move the presser block beyond "center" over the bed plate to permit the flange 25 to true the carton over the bed plate. After this truing the presser block is moved rearwardly until it is disposed centrally over the bed plate (as shown by the full lines in Fig. 2), in which position the suspending arms exert the required pressure to cause the flaps C and D to adhere to the gummed flaps A and B. In this position the presser block is permitted to stand a sufficient time to assure sufficient drying of the adhesive to secure the flaps. In this position the suspending arms are in alinement with the sustaining arms, and hence the presser block is practically locked at a position where the suspending arms exert a maximum pressure on the flaps of the carton.

Having thus described my invention, what I claim as new therein and desire to secure

by Letters Patent of the United States therefore, is:

1. In a carton sealing machine, a removable bed plate, a pair of sustaining arms, a rigid element suspended from the sustaining arms, a presser block pivotally carried by said suspending element, and means for limiting the pivotal movement of the presser block relative to the rigid suspending element. 55

2. In a carton sealing machine, a standard, a bed plate removably supported by the standard, a sustaining arm pivotally mounted on each side of the standard, means for limiting the movement of said arms in one direction, a rigid suspending element carried by said arms, a presser block pivotally carried by the suspending element, means for limiting the pivotal movement of the presser block relative to the suspending element, and means carried by the presser block for engagement with the bed plate to limit the movement of the presser block relative to the bed plate. 60

3. A carton sealing machine comprising in combination a bed plate, an arm having its pivotal point beneath the bed plate, a second arm pivotally suspended from the first mentioned arm and a presser block pivotally suspended from said second arm, 80 means for limiting the movement of the first mentioned arm relative to the bed plate, and means for limiting the movement of the presser block relative to the second mentioned arm. 75

4. In a carton sealing machine, a bed plate, a supporting means movable over the bed plate, a rigid arm suspended from said supporting means, a presser block pivotally suspended from said arm, means for limiting the movement of the supporting means and means for limiting the movement of the presser block relative to the bed plate. 85

In testimony whereof, I have signed my name to this specification, in presence of two 95 subscribing witnesses.

ALEXANDER L. SCHRAM.
